US00D674489S

(12) **United States Design Patent**
McCormack et al.

(10) **Patent No.:** US D674,489 S
(45) **Date of Patent:** ** Jan. 15, 2013

(54) **HANDLE FOR A MEDICAL DEVICE**

(75) Inventors: **Bruce M. McCormack**, San Francisco, CA (US); **Edward Fletcher Eyster**, St. Helena, CA (US); **Jeffrey D. Smith**, Clayton, CA (US); **Edward Liou**, Mountain View, CA (US); **Jonathan Carver**, Sausalito, CA (US); **Peter How**, Sunnyvale, CA (US); **Joshua Druker**, Redwood City, CA (US); **Martin Leugers**, San Francisco, CA (US); **Shigeru Tanaka**, Half Moon Bay, CA (US)

(73) Assignee: **Thayer Intellectual Property, Inc.**, San Francisco, CA (US)

(**) Term: **14 Years**

(21) Appl. No.: **29/369,901**

(22) Filed: **Sep. 15, 2010**

(51) LOC (9) Cl. **24-02**

(52) U.S. Cl. **D24/171; D24/133**

(58) **Field of Classification Search** D24/171, D24/133, 146, 147, 155, 188; D8/80, 83, D8/94, 97, 107, 303; 606/53, 79, 80, 167, 606/170, 114; 604/533

(57) **CLAIM**

The ornamental design for a handle for a medical device, as shown and described.

DESCRIPTION

FIG. 1 is a perspective view of a handle for a medical device of the present invention;

FIG. 2 is a left side view of the handle for a medical device of FIG. 1;

FIG. 3 is a right side view of the handle for a medical device of FIG. 1;

FIG. 4 is a rear view of the handle for a medical device of FIG. 1;

FIG. 5 is a front view of the handle for a medical device of FIG. 1;

FIG. 6 is a top view of the handle for a medical device of FIG. 1; and,

FIG. 7 is a bottom view of the handle for a medical device of FIG. 1.

The broken lines in the drawing views are included for the purpose of illustrating portions of a handle for a medical device that form no part of the claimed design.

1 Claim, 4 Drawing Sheets
